UNITED STATES PATENT OFFICE.

EARL CLARENCE WARWICK, OF KANSAS CITY, MISSOURI.

SPRAY.

1,020,937.

Specification of Letters Patent. Patented Mar. 19, 1912.

Application filed April 8, 1911. Serial No. 619,875.

To all whom it may concern:

Be it known that I, EARL C. WARWICK, a citizen of the United States, residing at Kansas City, in the county of Jackson and State of Missouri, have invented certain new and useful Improvements in Sprays, of which the following is a specification, reference being had to the accompanying drawings.

10 My invention relates to new and useful improvements in stands and sprays therefor and the primary object is to provide an improved means for spraying the articles carried on a stand in order to keep the same 15 in a fresh condition.

A further object resides in providing an improved form of spray provided with means for the draining of the water therefrom.

20 A still further object resides in providing a deflector for the spray disposed in such position as to cause the water to return to the drain.

With these and numerous other objects 25 in view, my invention consists in the novel features of construction, combination and arrangement of parts as will be hereinafter referred to and more particularly pointed out in the specification and claims.

30 In the accompanying drawings forming a part of this application, Figure 1 is an enlarged section through the spraying device. Fig. 2 is a detail perspective of the funnel member and deflector, Fig. 3 is an inverted 35 perspective of the top or screw plate and Fig. 4 is a reduced side elevation of a stand showing my improved spray applied to use thereon.

In carrying out my invention, I shall 40 refer to the drawings in which similar reference characters designate corresponding parts throughout the several views and in which 1 indicates a metallic stand comprising a base 2 mounted upon the supporting 45 legs 3 and a back plate 4. Extending from the back plate 4 toward the forward portion of the base 2 inclined at an angle downwardly, are the trays 5 which are made of wire mesh or any other similar material 50 desired, said trays being adapted to receive thereon vegetables and the like, and the outer ends thereof are bent upwardly at an angle to prevent the contents of said trays 55 from rolling therefrom.

Hingedly secured to the back plate 4 of said stand is a wire mesh covering 6,

whereby the stand containing eatables may be placed in the open air and will not be unsanitary, so far as flies and other insects are concerned. The sides 8 of the stand 60 may be made of metal or glass, the latter preferably, and hingedly secured to said back plate 4 is an additional cover 9, made preferably of glass, whereby all insects or other extraneous matter will be prevented 65 from injuring eatables carried on the stand.

The base 2 of the stand is adapted to be made hollow so that ice may be carried therein during the warmer periods of the year to retain the vegetables or other eatables in a fresh condition, and a waste water tank 10 is provided below the base with a cock 11 therein, whereby the water may be drained therefrom.

Extending through the base 2 of the stand 75 adjacent the back plate 4 thereof to a point above the trays 5, are any number of water pipes 12, I having shown but two in the drawings, said pipes being connected to the main or any other pipe leading thereto. 80

The upper ends of said pipes 12 are provided with the hollow circular heads 13, said heads being reduced in size and externally screw-threaded, as shown at 14. Mounted in each of the heads 13 is a brass 85 gauze wire 15, and a screw or top plate 16 of a diameter substantially equal to that of the head 13, is adapted to be threaded into engagement with the threaded portion of said head, said screw plate being provided 90 with a restricted opening 17 therein which is disposed so as to be positioned in alignment with the pipe 12 when said plate is mounted on the head.

A funnel-shaped member 18 terminating 95 in a pipe or the like 19 has an opening 20 in the lower portion thereof adjacent its point of termination, through which the pipe 12 extends, and the upper or flared portion of said funnel member 18 has 100 mounted therein or formed thereon a substantially basin-shaped member 21. This basin 21 has the bottom thereof completely perforated and is also provided with an opening 22, through which the upper portion of said pipe 12 extends, said basin being so disposed as to substantially receive the head 13 and the plate 16 therein.

Carried by the basin member 21 is a deflector or the like 23, the outer and effective 110 portion of which is disposed over and some distance above the opening 17 in the plate 16,

so that the water which is sprayed through said opening from the pipe will be deflected so as to cause a very fine spray or mist. The deflector 23, however, is so curved that the 5 water which is not sprayed therefrom, will pass downwardly to the basin 21 where it will be passed through the basin member 18 to the drain pipe 19.

It will doubtless be appreciated that with 10 a plurality of such sprays, as hereabove described, extending within a covered stand such as the one heretofore described, all eatables carried on the trays of said stand may be kept constantly in a fresh condition, in 15 view of the fine mist or spray which will occur from the water striking the deflector.

It will be understood that valves will be provided in the pipes 12 so that the water passing therethrough may be controlled, and 20 in order to provide water which is thoroughly cooled, I desire to extend the pipe 12 through the hollow base 2 of the stand, or have said pipe connected with an additional pipe which extends through said base, and 25 that portion of the pipe extending therethrough may be coiled, as shown at 24 in Fig. 1 of the drawings. This hollow base may be provided with ice, so that it will be seen that water passing through the coil 30 pipe 24 to the pipe 12 will be thoroughly cooled and the contents of the stand will be not only sprayed with a cooled water or mist, but also kept in a cool fresh condition from the cooled base of said stand.

35 It is a well known fact that vegetable and fruit dealers have difficulty displaying their eatables, particularly in warmer periods of the year, in view of the fact that the heat dries the same, and further, in view of the 40 unsanitary conditions which occur when displaying the same in the open air. With such a device as I have invented, however, all such eatables, whether readily perishable or not, may be displayed and at the same time 45 kept in a fresh and sanitary condition. Furthermore, when the spray is in operation, the contents of the trays of the stand will be kept thoroughly watered and the misty, water dripping condition of the stand will 50 doubtless attract considerable attention.

It will still further be seen that in view of the curvature of the deflector, that amount of water which is not sprayed outwardly over the contents of the trays, will be passed 55 down to the basin-like member to be drained away. In this manner, the stand, although receiving a spray or mist constantly, will never be in a thoroughly wet condition.

Furthermore, it will be seen that it is not 60 necessary to have these sprays constantly in

operation, so that when desired, the flow of water may be stopped, the glass cover removed and the mesh covering allowed to remain, and thereby the contents of the stand may be easily viewed by passersby and at 65 the same time be free from flies and other germ-carrying insects.

Furthermore, it will be seen that this device is of such simple construction as to be cheaply manufactured and one which will 70 be extremely effective in operation.

Although I have not heretofore stated such, it will be understood that this stand is to be made portable so that the same may be readily taken down and set aside when not 75 in use and made compact for shipping.

What I claim is:—

1. In a device of the character described, the combination with a water pipe, a hollow head formed on the upper end thereof and a 80 top plate removably engaged with said head and provided therein with a central restricted opening; of a funnel designed member through which said pipe extends terminating at its lower end in a drain pipe, the upper or flared portion of said funnel member being provided with a perforated basin encircling said head, and a deflector carried by said basin having a portion thereof disposed over the restricted opening in said 90 plate.

2. In a device of the class described, the combination with a water pipe, a hollow head formed at the upper end thereof, said head having a shoulder and an externally 95 threaded portion thereon, and a top plate provided with a shoulder and an internally threaded portion engaged with the threaded portion of said head, said plate being also provided with a restricted central opening; of a funnel-shaped member surrounding said head and plate, said funnel member terminating in a drain pipe and provided with an opening immediately adjacent said drain pipe, a perforated basin member 100 mounted in said funnel member and provided with a central opening through which said water pipe extends, and a deflector carried by the funnel member and disposed above the opening in said top plate, said 105 water pipe being also disposed through the opening in said funnel member, whereby the latter may be moved longitudinally of the water pipe when desired.

In testimony whereof I hereunto affix my 115 signature in the presence of two witnesses.

EARL CLARENCE WARWICK.
